Primary Examiner—Janice E. Seeger

(57) CLAIM

The ornamental design for an outdoor patio set poker table, as shown and described.

DESCRIPTION

FIG. 1 is a perspective view of a top side of the table;

FIG. 2 is a top view thereof;

FIG. 3 is a side view thereof;

FIG. 4 is a perspective view of a top side of an alternative embodiment of the subject invention; and,

FIG. 5 is a side view thereof.

The bottom side of the outdoor patio set poker table is flat and devoid of surface ornamentation.
